UNITED STATES PATENT OFFICE.

JOHN SCHUMACHER, OF LOS ANGELES, CALIFORNIA.

PLASTER BUILDING BOARD.

Application filed July 14, 1924. Serial No. 725,901.

This invention relates to a plaster board or the like and to the method of forming the same. The present invention appertains more especially to that class of plaster board having a plaster board and pliable fibrous sheets covering the same.

Such board is subject to rough handling and during its life is subject to strains at the edges whereby it may break and chip. 10 The primary object of this invention is to provide an article and method of producing the same, wherein the finished product consists of a plaster board having reinforces of pliable material embedded in and bound to 15 the plaster at the edges.

The product and method of manufacture are clearly set forth in the following description, reference being had to the accompanying drawings, wherein:

20 Fig. 1 is an enlarged cross-sectional view of a fragment of a board in its initial form showing the edge thereof before trimming; Fig. 2 is a perspective view of a fragment of the board shown in Fig. 1 after it has been 25 trimmed; Fig. 3 is a cross-sectional view of a fragment of a board before trimming and disclosing a variation of the structure shown in Figs. 1 and 2; Fig. 4 is a perspective view of the finished board of the type shown in 30 Fig. 3; Fig. 5 is a cross-sectional view of a fragment of a board initially of a different formation which is finally completed to produce the board shown in Fig. 4; Figs. 6, 7, 8 and 10 are different species of board in 35 their initially formed state before trimming; and Fig. 9 is the finished board of the species shown in Fig. 7.

The plaster board herein illustrated is in its general formation of the well known type 40 consisting of a relatively thin layer of plaster interposed between covering sheets preferably of paper. In its manufacture, the wet plastic material is fed between the sheets of paper and cut into lengths of convenient size for handling and finally dried. 45 In each of the figures, the cementitious body is indicated by 11 and is shown interposed between a top covering sheet 12 of paper or other fibrous material, and a bottom covering sheet 13. The terms top and bottom 50 covering sheets are used merely for purposes of convenience, inasmuch, as the board is alike on both sides. Broadly each species of board illustrated herein is the same, except for the reinforces which extend along 55 the edges.

Referring more particularly to Fig. 1, the top sheet 12 is of a greater width than the bottom sheet and during the formation and advance of the board, the top sheet 12 is 60 turned inwardly at the edges as indicated by 14 so as to provide a strip of reinforcement extending along the side edge. After 65 delivery from the formation devices, the board is trimmed by a saw or any other suitable trimming tool along the dotted line 15 of Fig. 1. This produces the finished product shown in Fig. 2 of the drawing. The covering sheet is of a material which will 70 form a bond with the plaster. For this reason bending of the board at the edges will not separate the reinforce from the body of the plaster. A unitary structure is thus 75 formed at the edges thereby strengthening the same without affecting the pliability.

Referring more particularly to Figs. 3 and 4, the covering sheets both top and bottom are made of a width greater than the initially formed board. The top covering sheet is turned inwardly and embedded in the plaster 80 body as indicated by 16. Similarly the bottom covering sheet 13 is turned inwardly and embedded in the plaster board as indicated by 17. The board is then trimmed along the line 18 producing the finished 85 board shown in Fig. 4. This board only differs from that shown in Fig. 2 by reason of having two parallel strips of reinforcement bound plaster.

The initially formed board shown in Fig. 90 5 varies in its formation from that heretofore described by embedding in the edge of the board a U-shaped reinforce having legs 19 and 20 directed into the plaster and a juncture 21 flush with the edge. The initially formed board is then trimmed along 95 the line 22 producing thereby the same product as is shown in Fig. 4.

Fig. 6 shows a board initially formed by turning in the top and bottom covering 100 sheets 12 and 13 and also inserting a U-shaped strip 23 of paper or the like. The edge of the board is then trimmed by cutting along the line 24, thereby producing a plaster board having four parallel reinforce 105 strips.

The structure shown in Figs. 7 and 9 are similar to that shown in Fig. 6. However, the marginal edges of the covering sheets 110 12 and 13 are turned inwardly at an angle, as indicated by 25 and 26. The U member 27 is inserted at the center of the edge, and

the board is then trimmed along the line 28 to form a finished board shown in Fig. 9.

The structure of the board shown in Fig. 8 is obvious from an inspection of the drawing. A single reinforce strip 29 is embedded in the edge of the board, and the latter then trimmed along the line 30. The board shown in Fig. 10 is formed of the same elements as that shown in Fig. 5, the U member 31 comprising the reinforce is turned in the opposite direction so that the legs are directed outwardly. The board is then trimmed along the line 32. Other variations embodying the inventive idea will be obvious to those skilled in the art.

Having thus described my invention, what I claim is:

1. The method of making an edge reinforced plaster board comprising applying a covering sheet to a plastic body, inserting into the edge longitudinally of said board a reinforcement strip, and trimming said edge of the green board.

2. The method of making an edge rein-

forced plaster board comprising applying a covering sheet to a plastic body turning a marginal edge of said covering sheet into the edge of said plastic body and trimming such reinforced edge of the green board.

3. The method of making an edge reinforced plaster board comprising applying covering sheets to a plaster body, turning marginal portions of said covering sheets into said plastic body, inserting longitudinally of said board, reinforcement strips at the edges thereof, and trimming the edges of the green board so formed.

4. The method of making an edge reinforced plaster board comprising applying covering sheets to a plastic body, turning marginal portions of said covering sheets into said plastic body and trimming the edges of the green board so formed.

In witness that I claim the foregoing I have hereunto subscribed my name this 30th day of June, 1924.

JOHN SCHUMACHER.
